SAFETY HAND CRANK STARTER FOR
ENGINES

Sherrod Riddell, Springfield, Ill.

Application May 28, 1937, Serial No. 145,195

1 Claim. (Cl. 123—185)

This invention relates to improvements in the hand starters for internal combustion motors, and it is the principal object of my invention to provide such a starter which at all times will protect the operator of a motor vehicle, as for instance a tractor, truck, automobile or also of stationary engines against serious injury resulting from a "kick back" caused by back-firing, or ignition and carburetor troubles, as it will 5 disconnect the crank from the engine instantaneously when such a "kick back" occurs.

Another object of my invention is the provision of a hand starter for internal combustion motors of a simple and therefore comparatively inexpensive construction, yet durable and highly efficient in use.

A further object of my invention is the provision of a hand starter for internal combustion and similar motors, the crank shaft of which 20 will compress a spring during the cranking operation while engaging the crank shaft with the engine starter shaft and when expanding under the influence of a "kick back" will engage a ratchet gear upon a spirally grooved boss on the 25 shaft which is prevented from reversing by means of a ratchet dog to slowly disengage the crank shaft from the starter shaft and positively preventing the crank shaft from backward rotation.

30 These and other objects and advantages of my invention will become more fully known as the description thereof proceeds, and will then be more specifically defined in the appended claim.

35 In the accompanying drawing forming a material part of this disclosure:

Fig. 1 is a top plan view of a safety hand starter for internal combustion engines constructed according to my invention.

40 Fig. 2 is a longitudinal section therethrough on line 2—2 of Figure 1.

Fig. 3 is a cross-section on line 3—3 of Figure 1.

As illustrated, the hand starter comprises 45 substantially a sleeve or housing 10 having an outer coupling member 11 formed integrally therewith adapted to be attached to the motor vehicle 12 by means of the bolts 13, 14 extending through said coupling member and carrying at 50 their inner ends the locking nuts 15, 16. These bolts extend also through another coupling member 17 supplementing the member 11 and held in engagement therewith by means of the nuts 18, 19 at the outer ends of the bolts 13, 14.

55 A stub shaft 20 extends through the coupling

members 11 and 17 and the housing 10 inwardly and carries at its inner end a pin engaging coupling member 20 to engage the crank shaft of the motor.

The outer end of the shaft 20 extends through 5 the member 17 and carries a pin 22 for the attachment of a starting crank 23 having recesses in which the pin 22 engages.

Between the coupling members 17 and 11 and their inner supplementing flanges, the stub shaft 10 carries a boss 24 provided with a spiral groove on its outer periphery which is generally designated 25 upon which travels a ratchet gear 26 having inner shoulders 27 engaging the spiral groove of the boss, while a pawl or dog 28 pivoted 15 intermediate its ends, as at 29, to a jaw or flange of the member 17 engages between the teeth of the ratchet gear 26, and is held in this engagement by means of the spring 30 secured in the inner flange or part 17.

20 A strong spring 31 is located within a chamber 32 in the housing 10, and wound about the shaft 20 between the inner wall of the boss 24 and the end wall of the chamber 32.

The operation of my device will be entirely 25 clear from the above description by simultaneously having reference to the drawing, and it will be clear that the crank can readily be engaged with the crank shaft of a motor under the compression of spring 31. As soon, however, 30 as the engine backfires the spring 31 will expand and will cause the shaft to be spirally moved outwardly to compel the ratchet gear 26 to follow this movement with its inner shoulders 27 to engage the spiral groove 25 of the boss to 35 slowly rotate the stub shaft 20 in the direction of cranking while the pawl or dog will hold the ratchet against turning backward, and thus any sudden powerful backward swing of the hand crank during cranking and backfiring will be 40 avoided and the frequent injuries sustained by the hands and arms, especially the wrists, will be positively avoided.

It will be clear that I have described and shown the preferred form of my device only as 45 one example of the many possible ways to practically construct the same and that I may make such changes in the general arrangement thereof and in the construction of its minor details as come within the scope of the appended claim 50 without departure from the spirit of my invention, and the principles involved.

Having thus described my invention, what I claim as new and desire to secure by Letters Patent is:

In a safety hand starter for internal combustion engines, a stub shaft, a housing member on said shaft to engage the motor crank shaft, a crank for rotating said stub shaft in clockwise direction, a boss on said stub shaft having a spiral groove in its outer periphery, and a ratchet gear having inner shoulders engaging the spiral groove on said boss, a spring wound about said stub shaft to be compressed during cranking and 10 to expand under backfire to engage said ratchet gear and move the same outwards along said boss and during such movement rotate the same and the stub shaft slowly in the direction of cranking to prevent injury, a second, flanged and

recessed housing member supplementing the first named member and bolted with the same to the engine to form a housing constituting a compact structure for the elements of the hand starter contained therein, a pawl pivoted intermediate 5 its ends to the flange of said housing member and engaging between the teeth of said ratchet gear, and a spring within the recess of said housing member to hold said pawl in engagement with said ratchet gear to form a means to prevent backward rotation of said ratchet gear and stub shaft. 10
